FUSE

Cheston M. Gilday, Sr., Springfield, Pa.

Application June 5, 1953, Serial No. 359,794

4 Claims. (Cl. 200—113)

1

The present invention relates to fuses and is concerned primarily with a fuse of the conventional plug type having a cartridge comprising a plurality of individual fuse elements which may be successively moved into effective position after one has been burned out. This application is a continuation in part of the abandoned application of Cheston M. Gilday, Sr., Serial Number 293,292, filed June 13, 1952, for "Universal Renewable Electric Fuse."

At the present time home owners, such as housewives and other owners and inhabitants of premises which include electric circuits, are often put to considerable inconvenience when a fuse burns out. Of course if such a fuse burns out during the daytime, and with other fuses available, the difficulty and annoyance may not be great but, in any event, the cost of replacing a fuse is fairly high and when it is considered that fuses often burn out at night and when replacements are not conveniently available, it will be recognized that when such an event occurs the occupant of the premises is put to great hardship.

With the foregoing conditions the present invention has in mind as its foremost objective the provision of a fuse of the conventional plug type which includes a cartridge in the form of a metallic tape that is punched at spaced intervals with small openings to provide what is in effect a plurality of individual fuse elements. This tape is suitably housed in the body of the fuse, and the fuse element at the free end is adapted to bridge a pair of contacts to complete the circuit that is controlled by the fuse.

Under ordinary conditions this tape is covered by a cup-shaped cap that is formed with a small window opening for inspection purposes and which cap may be removed when occasion demands so that after one fuse element has burned out the next one on the tape may be brought into effective position. An important object of the invention is the provision, in a fuse of the character indicated, of a cylindrical body of insulating material that is formed with a chamber which houses the tape and in which body the contact elements are arranged.

Still another object is to provide, in a fuse of the type noted, a disk-like member that is adapted to be forced down onto the fuse element which bridges the contacts by the cap so as to insure that the fuse element is in good effective engagement with the contact.

Yet another object of the invention is to provide, in a fuse of the character indicated, a cap element having a window opening arranged in

2

its top wall and which window opening is ordinarily closed by a piece of glass or similar transparent material.

Various other more detailed objects and advantages of the invention, such as arise in connection with carrying out the above-noted ideas in a practical embodiment, will in part become apparent and in part be hereinafter stated as the description of the invention proceeds.

10 The invention, therefore, comprises a fuse which consists essentially of a cylindrical fuse body of insulated material providing a chamber with contacts on the opposite sides thereof. Housed in this chamber is a cartridge in the form of a metallic tape that is punched at spaced intervals to define a plurality of individual fuse elements, with the fuse element at the end of the tape bridging the contacts. This fuse element is forced into engagement with the contacts by a disk member of insulating material which is in turn held in effective position by a cup-shaped cap having a window opening.

For a full and more complete understanding of the invention, reference may be had to the following description and accompanying drawing wherein:

Figure 1 is a transverse vertical section through the fuse of this invention as completely assembled.

Figure 2 is a side view partly in section and partly in elevation of the fuse body, disk and cap in exploded relation; and

Figure 3 is a top plan view of the fuse body with the cap and disk removed, this view being taken about on the plane represented by line 3—3 of the Figure 2.

Referring now to the drawing, wherein like reference characters denote corresponding parts, the fuse of this invention is shown as comprising three main elements. These are the fuse body, which is represented at B, a disk at D, and a cap at C.

The fuse body B comprises a cylindrical member 10 that is made of a good insulating material, such as porcelain, and which body defines a chamber 11. The porcelain body 10 is closed at the bottom, as indicated at 12, and this bottom carries a terminal 13 that is adapted to engage a complementary terminal in a conventional socket that is intended to receive the fuse. The lower portion of the body 10 is formed with coarse threads 14 which carry a correspondingly-shaped metallic sleeve 15 which is intended to be screwed into the socket aforesaid.

Carried by the body B is a metallic strip 16, having a foot 17 that engages the upper or inner

end of the terminal 13. This strip 16 terminates at the top in a contact 18.

A second metallic strip 19 is mounted in a wall of the body 10, substantially opposite to the strip 16, and the lower end of this strip 19 is in conductive engagement with the sleeve 15, as indicated at 20. The upper end of the strip 19 takes the form of a contact 21.

Immediately beneath the contacts 18 and 21 there is positioned a washer 22 of good insulating material, such as fiber, and which washer is formed with openings for accommodating the strips 16 and 19. Preferably, an insulating shield 23 is provided on the inner face of the strip 19 for a purpose to be later described.

A cartridge in the form of a metallic tape 24 is positioned in the chamber 11. This tape 24 is punched at spaced intervals so as to form openings 25 (see Figure 3) and it is the distance between each pair of openings 25 which determines one fuse element. The tape 24 is passed through an opening 26 in the strip 16 and also through a notch 27 formed on the upper inner edge of the wall 10 and about the contact 18. It is then passed over to the contact 21 and when so positioned, one of the openings 25 should lie substantially midway of the contacts 18 and 21.

The disk D is also of a good insulating material, such as fiber or plastic, and has a lower flat bottomed surface 28 that bears against the tape 24 where it engages the contacts 18 and 21. The upper portion of the disk D is preferably of a truncated conical shape 29, and is formed with a central opening or passage 30.

The cap C comprises a top wall 31 that is formed with a central opening 32 in which is positioned a piece of glass 33, or other desirable transparent material. Depending from this top wall 31 is a cylindrical skirt 34 which terminates in an internally threaded portion 35. These threads 35 are adapted to cooperate with threads 39 formed exteriorly on the upper portion of the cylinder body 10. When the cap C is threaded home it forces the disk D downwardly so that the bottom surface 28 of the disk urges the tape 24 into effective engagement with the contacts 18 and 21.

Operation

While the mode of operation and manner of using the fuse of this assembly is believed to be obvious from the illustration of the drawing and description of parts given, it may be briefly outlined as follows.

When a fuse burns out it will do so across the opening 25 because that is the zone of the smallest cross-sectional area, and hence the greatest resistance. When a fuse is burned out this condition may be readily ascertained by the inspection that is made possible by the window 33 in the cap and the passage 30 in the disk D.

After the inspection determines the fact that the fuse has burned out, all that is required is to unscrew the cap C and remove the cap, together with the disk D. That portion of the fuse between the opening 25, where the burning occurred and the contact 18, is now grasped and a pull exerted to unwind a sufficient length of the tape 24 to bring the next opening 25 into position midway between the contacts 18 and 21. When this position has been achieved the free end of the tape will lie over the contact 21 whereupon the disk D is again positioned and the cap C again threaded home.

It is evident that the washer 22 confines the cartridge 24 within the chamber 11, but the shield

at 23 prevents this cartridge from accidentally coming into engagement with the strip 19.

While a preferred specific embodiment of the invention is hereinbefore set forth, it is to be clearly understood that the invention is not to be limited to the exact constructions, mechanisms and devices illustrated and described because various modifications of these details may be provided in putting the invention into practice within the purview of the appended claims.

What is claimed is:

1. In a fuse of the character described, a cylindrical fuse body defining a chamber, a pair of contacts carried by said body, in spaced relation, a metallic tape in said chamber and formed with openings defining a plurality of individual fuse elements, the fuse element at the free end of said tape bridging said contacts, a disk of insulating material engaging that portion of the tape that extends over said contacts, and a cap forcing said disk against said tape.

2. In a fuse, a cylindrical body of insulating material having an upper externally threaded portion and formed with a chamber, a pair of contacts carried by said body in spaced relation, a metallic tape in said chamber and formed with a series of spaced openings defining individual fuse elements with the fuse element at the free end of said tape bridging said contacts, a disk of insulating material formed with a central passage and engaging the tape where it crosses said contacts, and a cap having a top wall formed with a window opening and a socket having a threaded portion engaging the threads on said body.

3. In a fuse having a pair of spaced contacts, a cartridge in the form of a metallic tape having a plurality of spaced apertures defining individual fuse elements with the fuse element at the end of said tape bridging said contacts.

4. In a fuse of the character described, a cylindrical body of insulating material defining a chamber and having a closed bottom, a terminal carried by said bottom, that portion of said body adjacent to said bottom being formed with coarse threads, a metallic sleeve of the same shape and fitted over said coarse threads, the upper portion of said body being externally threaded, a strip in said chamber having a foot engaging said terminal and formed with a contact at its upper end, a second strip carried by said body and having one end in conductive engagement with said sleeve and formed with a contact at its other end, said contacts being in spaced relation, a metallic tape formed with a series of spaced openings defining individual fuse elements with the fuse element at the free end of said tape bridging said contacts, a disk engaging said fuse element at the free end of said tape and formed with a central passage, and a cap having a top wall formed with a window opening in line with said passage and having a skirt formed with an internally threaded portion that is screwed onto the threads at the upper end of said body.
